UNITED STATES PATENT OFFICE.

FRANCIS A. WINSLOW, OF CHICAGO, ILLINOIS.

DOOR CLOSER AND CHECK.

SPECIFICATION forming part of Letters Patent No. 695,987, dated March 25, 1902.

Application filed April 5, 1901. Serial No. 54,442. (No model.)

To all whom it may concern:

Be it known that I, FRANCIS A. WINSLOW, a citizen of the United States of America, residing at Chicago, in the county of Cook and State of Illinois, have invented certain new and useful Improvements in Door Closers and Checks, of which the following is a specification.

My invention relates to certain improvements in door-closers, the object being to provide means for closing the door, which will be concealed from view, leaving no unsightly projecting portions, and, further, to provide means for limiting the maximum velocity of the door in closing, so as to prevent slamming, such means to be so inclosed and arranged with respect to the door as to be concealed and at the same time involve no objectionable variation in the form thereof.

To such end the invention consists in certain novel characteristics to be fully described below and definitely pointed out in the claims.

In the drawings, Figure 1 is a vertical median section of the door in line 1 1 of Fig. 2, the upper portion being broken away as immaterial to the invention. Fig. 2 is a vertical transverse section in the broken line 2 2 of Fig. 1. Fig. 3 is a horizontal section in the line 3 3 of Fig. 2. Fig. 4 is a view showing the same section as Fig. 3 with the door in its open position, and Fig. 5 is an elevation of the complete door.

Referring to these drawings, A represents a door-casing, and B a door, both being preferably of hollow construction, such as is common in many of the cast-metal doors now in use. The door is secured to the casing by means of ordinary butt-hinges C, and the edge 40 of the door at b is cut away to provide access to the interior thereof. Opposite this opening the casing is perforated at a' to receive the screw-threaded shank d of a double eyebolt D, the threaded end of the shank being screwed into an upright T-iron E, which is a part of the framework to which the casing is secured. The eyebolt contains two eyes d' d'', extending into the interior of the door and being eccentrically disposed with reference to the hinges. To the eye d' is secured a link F, to the other end of which is fastened a coiled spring G, extending across

within the interior of the hollow middle rail of the door and secured to a turnbuckle H, held against rotation by the walls of the door and provided with a screw I, the head of which, i, is countersunk in the socket b' in the free edge of the door. In the door here shown the upper portion is occupied by plate-glass J, the lower portion divided by means of a middle mullion K, separating two panels k k'. Within the hollow interior of the mullion K a lever M is pivoted between its ends at m, preferably by means of a plate m', secured to the door by screws m² m³. To the shorter upper end of the lever is pivoted a link N, the opposite end of which is pivoted to the eye d² of the eyebolt D. In the lower hollow rail of the door is a horizontal cylinder O, extending into the hinge-style and secured to the edge wall thereof by means of a screw o. The cylinder is preferably open at its opposite end and contains a piston o' on the end of a rod o², pivoted to the end of the lever M at o³. The end of the rod N, which is pivoted to the eyebolt, is preferably curved toward the hinge-axis, as seen at n, so as to clear the edge of the door when the latter takes the position seen in Fig. 4, and the link F is preferably curved in the opposite direction, so as to present its convex face f to the edge of the door and slide thereon to prevent the spring G from rubbing along that side as it is extended in the opening of the door. As the door swings from the closed to the open position the coiled spring is forcibly extended and the piston partially withdrawn from the cylinder, to which movement little resistance is offered, because of the construction of the piston, as shown, which is the common construction in pneumatic checks. When the door is released, the spring pulling eccentrically upon the casing draws the door shut, and the rod-and-lever connections between the eyebolt and the piston force the latter toward the closed end of the cylinder, compressing the air and checking the movement until sufficient air may escape. The lever M multiplies the range of movement of the piston, so as to give a much more satisfactory action and require less nicety of adjustment.

It should be noticed that all of the parts are wholly within the hollow door when the latter is closed and nothing is in sight to mar the

- ornamental or symmetrical appearance of the door. Furthermore, even when the door is open the parts exposed are so small and so inconspicuous that they are not objectionable.
- 5 The abundance of space provided by this arrangement gives opportunity for much greater range of adjustment, as well as much more even working of the spring. The screw-head is easily accessible at the free edge of the door 10 and affords means for adjusting the spring tension to the exact force desired.
- I claim as new and desire to secure by Letters Patent—
1. The combination with a casing, of a door 15 hinged to the casing and provided with an internal recess to receive and allow the lateral movement of an approximately vertical lever, a lever centrally pivoted in said recess, a checking-cylinder within the door and having 20 its plunger pivotally connected to one arm of the lever, and a link pivoted to the opposite arm of the lever, extending toward the hinged side of the door, and secured to the casing by a pivotal connection, substantially as described.
2. The combination with a side jamb or casing of a door hinged to the casing and provided with a recess extending from edge to edge thereof, a bearing secured to the casing 25 eccentrically to the pintle-line of the hinges and in the plane of the door, a tension-adjusting screw working in the free edge of the door and extending inward therefrom toward the opposite edge, and an extensible spring 30 located in said recess and having one end connected to said bearing and the other attached to said screw by connections allowing independent rotation of the latter, substantially as described.
3. The combination with a side jamb or casing, of a door hinged thereto and provided with a recess extending from edge to edge thereof, a bearing secured to the casing eccentrically to the pintle-line of the hinges, a 35 link pivotally attached to said bearing and extending into said recess when the door is closed, a tension-adjusting screw seated in

the opposite end of the recess with its head accessible at the door's free edge, an extensible spring located in said recess and having 50 one end connected to the free end of said link and the other attached to said screw by a swivel connection, a checking-cylinder and its plunger within the door, a lever centrally pivoted within the door and having one end 55 pivotally connected to said plunger, and a link pivotally connecting the opposite end of the lever to said bearing, substantially as described.

4. The combination with a casing, of a door laterally hinged thereto and provided with an internal recess extending from edge to edge, of a bearing secured to the casing upon the hinged side of the door and when the door is closed projecting into said recess, a curved 65 link pivoted to said bearing, a spring-coil having one end attached to the free end of the link, a nut secured to the opposite end of the coil, a socket secured in the recess at the free side of the door, and a screw arranged 70 to rotate without advance in said socket and extending inward in said recess and engaging said nut, substantially as described.

5. The combination with a door hinged to a casing and having the parts surrounding its 75 panels hollow, of a check-cylinder located in the cavity on one side of a panel, a link similarly located upon the opposite side of the same panel and pivotally connected to the casing on the hinge side of the door, an approximately vertical centrally-pivoted lever 80 lying in the cavity upon the third side of said panel and having its arms, respectively, pivotally connected to the link and the plunger of the check-cylinder, substantially as described. 85

In witness whereof I have hereunto set my hand at Chicago, in the county of Cook and State of Illinois, this 11th day of March, A. D. 1901.

FRANCIS A. WINSLOW.
